UNITED STATES PATENT OFFICE.

ROBERT EMMETT LENAHAN, OF BUELL, VIRGINIA.

BUNGHOLE STOPPER.

1,411,853.

Specification of Letters Patent.

Patented Apr. 4, 1922.

Application filed May 31, 1921. Serial No. 473,736.

To all whom it may concern:

Be it known that I, ROBERT E. LENAHAN, of Buell, in the county of Norfolk and State of Virginia, have invented certain new and useful Improvements in Bunghole Stoppers; and I do hereby declare the following to be a full, clear, and exact description of the invention, such as will enable others skilled in the art to which it appertains to

10 make and use the same.

In the painting or other coating of barrels and similar containers provided with a bung-hole from which the contents are to be discharged much care is required to prevent 15 the applied material from entering the barrel through such opening and deleteriously commingling with the substance to be placed in the barrel. In order to effectively guard against accidental entrance of the coating 20 material through the bung-hole I provide a simple and inexpensive device adapted for instant temporary plugging of the bung-hole and one which is capable of continued use and in connection with containers having varied sizes of bung-holes.

In the drawings, Figure 1 is a perspective view of my improved device. Figure 2 is a sectional view showing the stopper inserted in position in the bung-hole of a barrel. 30 Figure 3 is a front elevation.

I preferably form my improved stopper of metal and find that copper is especially suitable for that purpose. The device includes a truncated cone 1, the base of which is secured to a plate 2 which thus forms a lateral flange for the cone. To the smaller end of the cone is secured a strip 3 of spring metal, this strip being permanently attached to the cone centrally of the length of the 40 strip, with its free ends 4, 5, bent into spaced parallelism with the sides of the cone. The ends of the strip thus form a wedge for engaging the wall of a bung-hole and effectively retain the stopper in position. As 45 stated, the device is preferably made of metal, and I have found that a highly satisfactory and cheaply constructed article of the character described is produced by cutting a circular plate and removing its 50 center, the cone being joined to the plate

by soldering its base to the outer face of the plate. The truncated end of the cone is closed by the strip 3 soldered thereto, the strip thus becoming an inseparable part of the cone. As an aid in withdrawing the 55 stopper from the container I provide a grip piece 6 diametrically of the open end of the cone and form this preferably from strong wire.

The advantages of my invention will be 60 apparent. It is manifest that the device, a one-piece article, is readily fitted in the bung-hole of a barrel or other container and that when so inserted it effectively closes the bung-hole as against entrance of the 65 substance with which a barrel is being coated, it being unnecessary that care be exercised by the one applying the paint since the temporary stopper precludes all application of the paint so closely adjacent the 70 bung-hole as to be harmful. It is further to be observed that the construction of the device is such that it is adaptable for various sizes of openings.

I claim as my invention:

1. A temporary stopper for bung-holes including a cone-like member, and a flexible metallic strip secured to said cone-like member, the ends of said strip extending in spaced parallelism with said cone-like member and forming a wedging means for securing said stopper in a bung-hole. 75

2. A temporary stopper for bung-holes including a cone-like member having its base terminating in a lateral flange, and means secured to the opposite end of said cone-like member for wedging it in position in a bung-hole. 85

3. A temporary stopper for bung-holes including a cone-like member having its base terminating in a lateral flange, and a flexible metallic strip secured to the smaller end of the cone, the ends of said strip extending in spaced parallelism with said cone, and forming a wedging means for holding 95 said stopper in a bung-hole.

In testimony whereof I have signed this specification.

ROBERT EMMETT LENAHAN.
